(57) **CLAIM**

The ornamental design for a pocketed unisuit, as shown and described.

DESCRIPTION

FIG. 1 is a front elevational view of a pocketed unisuit showing my new design;

FIG. 2 is a rear elevational view thereof; and,

FIG. 3 is a side elevational view thereof.

The broken lines showing portions of the human form in FIGS. 1-3 show the design in use and form no part of the claim.

The broken lines shown throughout the views on the surface of the garment represent stitching.
